UNITED STATES PATENT OFFICE.

HENRY H. DECREMER, OF LUXEMBURG, WISCONSIN.

PERMUTATION LOCK.

Application filed May 6, 1922. Serial No. 558,892.

To all whom it may concern:

Be it known that I, HENRY H. DECREMER, a citizen of the United States, residing at Luxemburg, in the county of Kewaunee and 5 State of Wisconsin, have invented certain new and useful Improvements in Permutation Locks, of which the following is a specification.

The present invention relates to permutation locks and more particularly to devices 10 of this nature which are adapted to be used in connection with hasps and the like. The principal object of the invention is to provide a permutation lock of simple and efficient 15 structure, which is reliable in operation, inexpensive to manufacture, and well adapted to the purpose for which it is designed.

Another important object of the invention 20 is to provide a lock of this nature having a slideable bolt which may be held in adjusted position by a plurality of slideable tumblers.

With the above and numerous other objects in view, as will appear as the description 25 progresses, the invention resides in certain novel features of construction, and the combination and arrangement of parts as will be hereinafter more fully described and claimed.

30 In the drawing:—

Figure 1 is a perspective showing the permutation lock in conjunction with a hasp,

Figure 2 is a longitudinal section taken therethrough,

35 Figures 3 and 4 are transverse sections taken approximately on the lines 3—3 and 4—4 of Figure 2,

Figure 5 is a detailed longitudinal section taken substantially on the line 5—5 of Figure 2,

Figure 6 is a detailed longitudinal view taken substantially on the line 6—6 of Figure 5 looking downwardly,

Figure 7 is a transverse section taken substantially on the line 7—7 of Figure 6,

Figure 8 is a similar view taken substantially on the line 8—8 of Figure 6,

Figure 9 is a disassembled perspective of the permutation lock,

50 Figure 10 is a detailed perspective of one of the tumbler slides,

Figure 11 is a similar view of another of the tumblers, and

Figure 12 is a perspective of the permutation locks showing the same used in a 55 slightly modified form.

Referring to the drawing in detail it will be seen that the hasp shown in Figure 1 includes the stationary leaf 13 which has hinged thereto the movable leaf 14 having a 60 suitable aperture 15 at its end for receiving the hollow open bolt engaging member 16. My permutation lock is mounted on the movable leaf 14 and comprises a housing formed of a pair of sections 18 each of which is provided with a longitudinally located groove 19 and a plurality of transversely extending grooves 20 the depth of which are substantially greater than the depth of the longitudinal groove 19. A filler block 21 is received between the two sections 18 adjacent one of their edges and these parts are firmly held together by rivets or in any other suitable manner. The slideable bolt 22 includes a shank 23 and a pair of notched ledges 24 70 one on each side thereof and the notches 25 of these ledges 24 are positioned in alternate relation with each other. These ledges 24 are slideable through the longitudinal grooves 19 of the sections 18 while the shank is slideable between the sections themselves opposite to the filler block 21. A plurality of tumbler bars are slideably mounted in the grooves 20 of the sections 18 and these bars are indicated generally by the numerals 27 75 and 28. The tumbler bar 27 is provided intermediate its ends with a notch 29 and a shoulder 30 is slightly spaced therefrom. The tumbler bar 28 is likewise provided with a notch 31, and a shoulder 32 but this shoulder 32 is formed immediately adjacent the notch 31. These tumblers are specifically indicated by the numerals 1 to 12 inclusive as is shown in Figure 1. The tumbler blocks 27 and 28 are arranged as may be desired 80 and by changing the position or the number of the various tumblers, the combination of the permutation lock may be readily changed.

The operation of the permutation lock 100 may now be understood. It is the purpose of the notches 29 and 31 to be brought into registry with the grooves 19 thereby allowing the bolt 22 to be freely slid into and out of engagement with the member 16. As 105 may be seen from an inspection of Figures

3, 4, 7 and 8 the tumbler blocks indicated by the numeral 27 may be pulled out farther than those indicated by the numeral 28. When any of the notches 29 or 31 are out of alignment with the grooves 19, of course, the bolt 22 is prevented from sliding since the bodies of the tumbler blocks will be in the notches 25. The user of the lock will be familiar with which of the tumblers are of the formation similar to those indicated by the numeral 27 and also those which are formed similar to those indicated by the numeral 28 and thus pull or push the tumblers in proper position to bring the notches thereof in alignment with the grooves 19 whereby the ledges 24 will be free to slide and the bolt will therefore be released.

As is indicated to advantage in Figure 2 a longitudinally extending slot 35 is provided adjacent one end of the shank 23 of the bolt 22 and a pin passes therethrough thereby limiting the movement of the bolt. This bolt is provided at the end of its shank with an angular extension 36 so that it may be readily operated when free to do so.

Attention is called to the fact that the filler block 21 is wider than the shank 23 and that the shoulders 32 will engage therewith so that these tumbler blocks 1 to 12 inclusive may not be pulled all the way out of the lock.

Having described my invention with some degree of particularity it is thought that the construction and operation thereof will now be understood without a more detailed description. Numerous changes in the con-

struction, combination and arrangement of parts may be resorted to by anyone skilled in the art without departing from the spirit of the invention as hereinafter claimed.

40

Having thus described my invention what I claim as new is:—

A permutation lock of the class described comprising a pair of spaced sections provided each with longitudinally extending grooves and a plurality of transversely extending grooves, a bolt slidably mounted between the sections and including a shank, a pair of ledges on one edge of the shank one on each side thereof, said ledges provided with a plurality of notches adapted to be brought into registry with the transversely extending notches of the sections, and a plurality of slidable tumblers provided with notches and mounted in the transverse grooves of the sections and adapted to extend through the notches of the ledges and provided with notches adapted to be brought into registry with the longitudinally extending grooves of the sections so as to allow the bolt to move freely, a filler block between the sections, said tumblers provided with stops spaced irregularly in respect to the notches thereof in the manner and for the purpose specified.

65

In testimony whereof I affix my signature in presence of two witnesses.

HENRY H. DECREMER.
